INVENTOR

Francis M. Hatch,

BY

Chester Bradford,

ATTORNEY.

UNITED STATES PATENT OFFICE.

FRANCIS M. HATCH, OF SOUTH BEND, INDIANA.

DELIVERER OF PACKAGES FROM MOVING CARS.

SPECIFICATION forming part of Letters Patent No. 614,863, dated November 29, 1898.

Application filed March 7, 1898. Serial No. 672,891. (No model.)

To all whom it may concern:

Be it known that I, FRANCIS M. HATCH, a citizen of the United States, residing at South Bend, in the county of St. Joseph and State 5 of Indiana, have invented certain new and useful Improvements in Deliverers of Packages from Moving Cars, of which the following is a specification.

The object of my invention is to produce a 10 device for delivering packages or other similar articles from moving railway-cars in such a manner as to substantially counteract the effect upon such packages produced by the movement of the train.

15 It consists, generally speaking, of a delivery-wheel to be actuated from one of the car-axles, the periphery of which contains recesses or pockets for the articles and which is so speeded as to move at substantially the 20 same rate that the train is moving forward, so that by arranging the discharge-point at that side of the delivery-wheel which is running toward the rear of the train the speed of the train will be substantially counteracted 25 and the article dropped at about the point where it is thrown from the train, and thus secure that the force with which such article comes in contact with the platform or ground will not much exceed the ordinary force of 30 an article of similar weight in merely dropping through such a distance.

Referring to the accompanying drawings, which are made a part hereof and on which similar letters and numerals of reference indicate similar parts, Figure 1 is a side elevation of one end of a railway-car provided with a delivery mechanism embodying my present invention; Fig. 2, a view of said mechanism and adjacent parts as seen when looking in the direction indicated by the arrows from the dotted line 2 2 in Fig. 1; Fig. 3, a horizontal sectional view as seen when looking downwardly from the dotted line 3 3 in Fig. 1, a portion of the floor of the car being broken away to 45 show the mechanism beneath; Fig. 4, a detail sectional view, on an enlarged scale, of the delivery-wheel separately on the dotted line 4 4 in Fig. 3; and Fig. 5, a detail view showing the clutch more plainly.

50 In carrying out my said invention I mount a shaft 1 in suitable bearings 2, preferably on the truck-frame 3 of the car. On one of

the ordinary car-axles 4 I have shown a sprocket-wheel 5, from which a chain belt 6 runs to a similar sprocket-wheel 7, loosely 55 mounted on the shaft 1. A friction-clutch 8, which is adapted to be operated by lever 9, is a suitable means for causing the rotation of the shaft 1, as will be readily understood.

Upon the outer end of the shaft 1 is the delivery-wheel A, which is composed of an ordinary hub and spokes, with a rim a' at the end of said spokes and wings a extending out from said rim, the spaces between the wings being the pockets or recesses which 65 constitute receptacles for the packages or other articles.

Surrounding the delivery-wheel is a casing B, which is somewhat in the form of an ordinary fan-casing, having a hopper or opening 70 b in the upper side to receive the bundles and a discharge outlet or mouth b', arranged tangentially to its lower side, through which the bundles are to be delivered. This discharge-outlet may be curved from the car 75 side somewhat, as best shown in Fig. 3, in order that the bundles may be given a slight outward movement at the time they are delivered, and thus insured from being thrown or drawn under the car. 80

While I have shown sprocket-wheels, a chain belt, and a clutch as the means for operating my delivery-wheel, it is obvious that friction-pulleys or other similar or suitable propelling mechanism may be substituted therefor without departing from my invention, which consists not in the particular means of driving it, but in a delivery-wheel mounted and operated in the manner described. 85

The operation of my invention may be 90 briefly recapitulated as follows: Ordinarily the shaft 1 is quiescent, the sprocket-wheel 7 running loosely thereon. As the train approaches a point where it is desired to deliver an article, as a bundle of papers, the person 95 having charge of the matter is able to place said article within the pocket or recess in the upper side of the delivery-wheel through the hopper-like opening in its casing. When the point or station has been reached where it is 100 desired to deliver the article, he operates the lever 9, thus throwing the clutch into engagement and setting the shaft 1 in motion, when the article to be delivered is carried around

between the rim of said wheel and the surrounding case from the point where it is placed in the delivery-wheel to the delivery-outlet, where it is discharged, the impulse 5 being thus in the opposite direction to that in which the train is moving. The result is that the article drops without much force at substantially the point where it leaves the deliverer, instead of being impelled with great 10 force in the direction of the motion of the train, as is ordinarily the case.

Having thus fully described my said invention, what I claim as new, and desire to secure by Letters Patent, is—

- 15 1. The combination, in a deliverer of packages from moving cars, with a car and a car-axle, of a delivery-wheel, a suitable casing therefor, and means for driving said delivery-wheel from an axle of the car.
- 20 2. The combination, with a car, of a pack-
age-deliverer consisting of a suitable casing

having an opening or hopper through which articles may be introduced, a delivery-opening tangential to said casing and opening in the direction reverse to that of the motion of the train, a delivery-wheel having suitable pockets or recesses in its periphery and positioned within said casing, a shaft for said delivery-wheel, driving means connecting said shaft and the axle of the car, and means 25 for throwing said driving means into and out of engagement whereby the delivery-wheel may be impelled or permitted to remain at rest.

In witness whereof I have hereunto set my 35 hand and seal, at Indianapolis, Indiana, this 3d day of March, A. D. 1898.

FRANCIS M. HATCH. [L. S.]
